UNITED STATES PATENT OFFICE

JAMES BABIN McHUGH, OF AMBROSIA, LOUISIANA.

BACK-BAND.

SPECIFICATION forming part of Letters Patent No. 308,974, dated December 9, 1884.

Application filed September 1, 1884. (No model.)

To all whom it may concern:

Be it known that I, JAMES B. McHUGH, of Ambrosia, in the parish of East Baton Rouge and State of Louisiana, have invented a new and Improved Back-Band, of which the following is a full, clear, and exact description.

This invention consists in a back-band for draft-horses or other draft-animals, composed of a web of woven material with attached end 10 skirts of leather, and buckles and straps applied to the ends of the band, to provide for engagement of the band with the trace-chains of the vehicle, substantially as hereinafter described, and whereby not only is greater comfort secured for the horse, but provision is 15 made for changing the connection of the band from one part of the chains to another and for lengthening or shortening the band, as desired, also for putting on the band without 20 unfastening either end of the chains, and great durability for the band is secured.

Reference is to be had to the accompanying drawings, forming part of this specification, in which similar letters of reference indicate 25 corresponding parts in both the figures.

Figure 1 is a view in perspective of a back-band embodying my invention, and Fig. 2 a like view of one end of the band, showing a modified attachment of the fastening-strap thereto.

A indicates the body part or main portion of the band, made of a web of woven material.

On each end of this web is stitched a leather skirt, B, and outside of this a buckle-holding strap, C, is secured by means of rivets b, arranged to pass through both the skirt and web.

D indicates the fastening-straps at the ends of the band, and which are passed through 40 any one of the links of the trace-chains E, one of which only in part here is shown by dotted lines. This mode of attaching the band to the trace-chains provides for putting on the band without unfastening either end of the 45 chains and for changing the connection of the

band with different parts of the chains, as occasion may require. Said straps D are also made to lengthen and shorten.

In Fig. 1 of the drawings the fastening-straps D are shown as secured by rivets c at 50 their one end to the skirts B, below either buckle G, carried by the straps C, and pointing downward, and the other or free end portion of said fastening-straps is provided with a series of holes, d, for engagement of said straps with the tongues of the buckles. To connect the band with the chains the free end of either fastening-strap D is passed through a link in 55 its respective chain and then engaged with the buckle, each fastening-strap being let out or taken up, as required.

In Fig. 2 of the drawings the fastening-strap D is not shown as riveted to the skirt B, but as wholly detachable therefrom. In this case said strap has not only the take-up perforations d in the one end portion of it, but one or more like perforations in its other end portion, which is first engaged with the buckle, then the other end passed through a link in the chain, and afterward also engaged with 65 the buckle. This mode of connecting the fastened straps affords great facility for repair.

A back-band constructed as described will 70 be found much more comfortable to the horse than the ordinary back-bands in use.

Having thus described my invention, I claim as new and desire to secure by Letters Patent—

In a back-band, the body or main portion 80 provided at its ends with skirts and buckles, in combination with the chain or trace carrying loops adjustably suspended from said buckles or from said skirts and buckles, substantially as and for the purpose set forth. 85

JAMES BABIN McHUGH.
